UNITED STATES PATENT OFFICE.

JUDDIE JOHNSON, OF STOCKHAM, NEBRASKA.

HOG BUTCHERING AND SCALDING TABLE.

1,315,028.

Specification of Letters Patent.

Patented Sept. 2, 1919.

Application filed March 22, 1919. Serial No. 284,290.

To all whom it may concern:

Be it known that I, JUDDIE JOHNSON, a citizen of the United States, residing at Stockham, in the county of Hamilton and 5 State of Nebraska, have invented certain new and useful Improvements in Hog Butchering and Scalding Tables, of which the following is a specification, reference being had to the accompanying drawings.

10 This invention relates to an improved table and derrick boom for scalding, butchering and cleaning hogs and the like, particularly adapted to use on farms and elsewhere.

15 One of the objects of the invention is to provide a table of this kind, mounted on runners, whereby the table may be moved from one place to another.

The invention further aims to provide 20 means for the support of a hog, and means whereby the hog may be raised and lowered in a barrel of scalding water, for scalding the hog.

The invention further aims to provide 25 means whereby the barrel may be supported on different inclines, and means for holding the derrick boom in such positions with regard to the inclinations of the barrel, whereby the hog may be raised and lowered 30 more conveniently according to the scalding result desired.

It is a further aim of the invention to afford improved means for holding the derrick boom in different adjusted positions.

35 As a further object of the invention it is the aim to afford means for supporting the hog straight up and down after it is scraped, whereby the hog may be cleaned on its interior.

40 Also it is the aim to provide bracing means for reinforcing the sides of the rectangular derrick boom, and also to afford bracing means for reinforcing the structure of the table.

45 While the structure in the present illustrations is deemed preferable, a reduction of the structure to a practical form for commercial purposes may require alterations. The right to these alterations is claimed, 50 provided the alterations fall within the scope of what is claimed.

The invention comprises further features and combination of parts, as will be herein-after set forth, shown in the drawings, and 55 claimed.

In the drawings:

Figure 1 is a view in side elevation of the improved table constructed in accordance with the invention, and in this figure the derrick boom is shown in different position 60 in dotted lines.

Fig. 2 is a plan view of the same.

Fig. 3 is a longitudinal sectional view on line 3—3 Fig. 2.

Fig. 4 is a sectional view on line 4—4 of 65 Fig. 1, at a point through the hoisting drum.

Fig. 5 is a transverse sectional view on line 5—5 of Fig. 1, illustrating the intersecting braces, which are clamped together 70 at the point of their intersection by means of a clamp.

Fig. 6 is a detail sectional view through the clamp shown in Fig. 5.

Referring to the drawings 1 designates 75 a frame as a whole, and this frame comprises the runners or base beams 2 and the super-imposed beams 3, there being uprights 4 rising from the runners and in turn supporting the super-imposed beams 3. Cross- 80 intersecting braces 5 connect the runners and super-imposed beams, as shown clearly in the cross-sectional views of the structure. These braces 5 are designed to reinforce the structure and to insure rigidity. In order 85 to insure this result the braces at their points of intersection are clamped together by the clamping members 6 having securing bolts 7. Mounted upon the super-imposed beams 3 is 90 a bed or table plate 8. The forward portions of the runners 2 are provided with extensions 9, on which transverse bars 10 are secured. A barrel containing scalding water or the like is designed to be supported on these bars 10, as shown clearly in Fig. 1. 95 The end edge 11 of the bed or table plate 8 is provided with a semi-circular cut-away portion or recess 12. This cut-away portion conforms to the annular contour of the barrel, in order to hold the barrel in its proper 100 position. It is obvious that since the bars 10 are spaced as shown, the barrel may be tilted on different inclinations, as shown clearly in dotted lines. In order to tilt the barrel in such a manner the corner of the 105 barrel engages between two of the bars 10. The barrel is tilted in this manner, in order to accommodate itself to the position of the derrick boom.

Mounted in suitable bearings of the super- 110

imposed beams 3 is a shaft 14, the ends of which are provided with suitable cranks. Keyed upon the shaft is a hoisting drum 15. On one end of the shaft 14 and secured by 5 screw bolts 16 to one end of the drum is a ratchet 17. A suitable pawl 18 is mounted upon a pin of one of the super-imposed beams 3, and engages the teeth of the ratchet, in order to hold the drum and the shaft in 10 different positions.

A derrick boom 19 is afforded, and this boom comprises side bars 20, which are pivotally mounted upon the bolts 21, which pass through the side bars and through the beams

15 3. The outer ends of the side booms 20 are connected by the cross-piece 21^a, there being clamps 22 connecting the corner junctions of the side bars 20 and the cross-piece 21^a. These clamps are constructed of sheet metal 20 and are designed for straddling the corners of the boom, and are secured in place as at 23, thereby insuring strength and rigidity, hence reinforcing the boom against strains.

Passing through the lower end of one of 25 the side bars 20 is an eye-bolt 24, the same being secured in position by the nut 25. The elongated rod 26 has one end connected in the eyebolt 24, and its other end terminates in a lateral hook 27, to engage any one of 30 the apertures designated 28, 29 and 30, respectively. It is obvious that by engaging the hook 27 in the aperture 28, the derrick boom will be supported in a vertical position, whereby the hog may be so suspended 35 after it is scraped, in order that the entrails may be removed.

By engaging the hook 27 in the aperture 29, thereby supporting the boom in an inclined position, the barrel being also inclined, the hog may be raised and lowered 40 in the barrel (which is supplied with scalding water, for the purpose of scalding the hog).

Obviously by inserting the hook 27 in 45 the aperture or opening 30, and arranging the barrel vertically, as in full lines in the drawings, the hog may be lowered into the barrel, subsequently to having been hoisted from the ground.

50 The cross-piece 21 on the boom has suspended from a hook or an eye 31, a pulley 32, over which a rope 33 passes. One end of this rope or cable is supplied with a hook 34, and the other end of the rope or cable is connected to the drum. By connecting the hook 55 of one end of the cable to the hog, while on the ground, and by imparting motion to the

drum, winding the cable thereon, the hog may be hoisted, and subsequently lowered into the barrel.

Connected to eyes 35 upon opposite uprights 4 are hooks 36, the hook extremities of which are designed to engage, one with one of the cranks of the shaft, to prevent retrograde motion of the shaft, in case the pawl is not employed. Secured at 37 to the 60 outer faces of the runners 2 are blocks 38 provided with recesses 39 having abutment shoulders 40, which are engaged by the lower ends of the side bars of the boom, thereby 65 limiting the boom in its vertical position. 70

The invention having been set forth, what is claimed as new is:

1. In an apparatus as set forth, the combination with a frame provided with a supporting bed or table, of a lifting boom 75 comprising side bars, straddling and being pivoted to one end of the frame, braces secured to the sides of the frame provided with recesses, said recesses having abutment shoulders to be engaged by the ends of the 80 side bars of the boom, when the ends engage the recesses, thereby supporting the boom in a vertical position.

2. In an apparatus as set forth, the combination with a frame provided with a supporting bed or table, of a lifting boom comprising side bars, straddling and being pivoted to one end of the frame, braces secured to the sides of the frame provided with recesses, said recesses having abutment shoulders to be engaged by the ends of the side 85 bars of the boom, when the ends engage the recesses, thereby supporting the boom in a vertical position, and means for holding the boom in different adjusted inclined positions. 90

3. In an apparatus as set forth, the combination with a supporting table frame, of means at one end of the table supporting frame for holding a barrel in various inclined positions, a boom pivotally mounted 100 on the supporting table frame near its opposite ends, and means for holding the boom in various corresponding inclined positions relatively to the positions of the barrel, whereby a hog, which may be suspended 105 from the boom, may be raised and lowered in the barrel.

In testimony whereof I hereunto affix my signature in the presence of two witnesses.

JUDDIE JOHNSON.
